UNITED STATES PATENT OFFICE.

WILLIAM J. HART, OF ST. JOSEPH, MICHIGAN, ASSIGNOR OF ONE-FOURTH TO ALONZO W. PANGBORN AND ONE-FOURTH TO FRANCES D. PANGBORN, BOTH OF ST. JOSEPH, MICHIGAN.

SHOE-LACING DEVICE.

Application filed April 9, 1923. Serial No. 630,927.

To all whom it may concern:

Be it known that I, WILLIAM J. HART, a citizen of the United States, residing at St. Joseph, in the county of Berrien and State of Michigan, have invented certain new and useful Improvements in Shoe-Lacing Devices, of which the following is a specification.

My invention relates to a device for simplifying the lacing of shoes and by means of which the lacing is accomplished with greatest ease and without the necessity of tying the laces.

The object of the invention is to furnish the shoe with rollers instead of the usual eyelets through which the laces run, and on account of the diminished friction in drawing the lace tight, the shoe can be put on in a much shorter time than it usually takes.

Another object of the invention is to furnish a clasp for holding the lace tight instead of tying the same.

In the accompanying drawing, the subject matter of the present invention has been illustrated, and;

Figure 1 shows a shoe with the device in position;

Figure 2 is a side elevation in partial section of the roller;

Figure 3 is a top plan view of Figure 2;

Figure 4 is a longitudinal section through the lace clasp in open position;

Figure 5 is a similar view to Figure 4 with the lace tightened and held securely by the clasp; and

Figure 6 is a view similar to Figure 2 of a slightly modified form of the roller and bracket.

In place of the usual eyelets furnished in shoes, I provide small brackets 10, each carrying a grooved roller 11 secured at the edge 12 of the shoe 13 by means of fingers

9. The roller 11 is journaled on a pivot with trunnions 14, see Figures 2 and 3. A sufficient number of these brackets and rollers is furnished along the edges of the upper of the shoe, as seen in Figure 1.

The lace 15 is preferably secured at the lower end over the tongue of the shoe as at 16 in a pair of eyelets of the usual kind, but from there the lace passes alternately through a right and left hand bracket over its roller, and it will be evident that after

the foot has been pushed into the shoe, it will be comparatively easy to draw the lace upwards to close the two side edges 12 over the tongue, as indicated in Figure 1.

Instead of the construction illustrated in Figures 2 and 3, it might at times be preferable to use a bracket 17, as indicated in Figure 6. Instead of bracket 10 being open on three sides, this bracket 17 is closed on the front and rear and only open on the two opposite sides through which the lace passes. The rivet 18 in this case functions as a journal for the roller 19, while the bracket 17 has a tail 20 for securing it to the leather by means of a short rivet 21.

Referring now particularly to Figures 4 and 5, these show the construction of the clasp or securing means for the lace after it has been tightened. This clasp consists of a casing 22, which is hollow and may be made in symmetrical halves, which may be riveted together as at 23. In the chamber 24 formed in the casing 22 are pivoted as at 25 a pair of dogs 26. These dogs are pressed outwardly by means of a spring 27 rigidly secured in the chamber 24. This journal 25 is carried by a push button 28, which is slidably mounted at the lower end of the casing 22 and projects with a small head 29 through the bottom of the casing.

The button 28 is provided with two annular grooves 30 and 31 situated one above the other and placed slightly apart. In the corresponding groove 32 furnished in the casing 22 is lodged a split ring or oval spring 33, which fits tightly in one of the grooves 30 or 31, so as to hold the button 28 either in drawn out or pushed in position.

The annular groove 32 in the casing is of sufficient depth to permit the opening and closing of the spring when the button 28 has passed through it.

As indicated in Figure 4, the lower walls 34 of the casing abut against the edges of the dogs, when the latter are drawn upwards by the abutment 28 in its lowered position. In its pushed in position, as indicated in Figure 5, the head 28 permits the edges of the dogs 26 to disengage from the walls 34, when the spring 27 acts on the dogs and pushes them apart.

In perpendicular direction through the casing 22 are run a pair of parallel pas-

sages 35, and passing through the chamber 24. These passages are intended to receive the ends of the lace 15, as indicated in Figures 4 and 5, and the passages 35 are so positioned that when the button 28 is pushed inwards, the springs 27 will spread the dogs 26 apart to abut against the part of the lace 15 that is situated in the chamber 24 and in this manner engage it tightly 10 and prevent their sliding down through the casing again.

The clasp or clamp 22 may be secured to one side of the shoe top or may be entirely loose therefrom, and it may be made in 15 many different shapes and constitute an ornament for the shoe.

The use of the device is as follows: With the lace loosened and the shoe open, the wearer pushes his foot into the shoe in the 20 usual manner and draws the lace upwards, when it will slip easily over the rollers and quickly draw the edges of the top of the shoe together. Each end of the lace is then passed through its respective passage 35 in 25 the clamp or clasp 22, with the button 28 previously drawn out so that the lace ends pass easily through the casing. While holding the lace ends drawn up tightly, the button 28 is thereupon pushed inwards in the 30 casing, when the dogs 26 will snap outwardly and grip the lace and hold it securely in the casing. The ends of the lace may now be left hanging or tied in a loose knot, but it is evident that this knot has nothing to 35 do with keeping the lace taut and the knot is only made to prevent the ends of the lace from dragging and to make the shoe look tidy.

It is evident that this clasp or clamp may 40 be used without the rollers and their brackets on shoes having ordinary eyelets, or it may be used for other articles having laces or tape that needs securing. In order to remove the shoe, all that is necessary is to 45 draw the button 28 outwards, when the dogs 26 will release the ends of the lace 15, which will then slide downwardly through the passages 35, and as the lace will slip easily over the rollers 11, it is evident that opening of 50 the tops of the shoe will be accomplished without great effort.

Having thus described the invention what is claimed as new is:

1. A device for lacing shoes and the like 55 comprising guides for the lace along the edges to be drawn together, and means for firmly holding the ends of the lace after tightening; said means including a casing having a chamber and passages for the lace running through said chamber, a sliding member in said casing, a pair of dogs pivoted on said sliding member and tending 60

to grip the lace, and a locking element for said sliding member.

2. A device for lacing shoes and the like 65 comprising guide rollers for the lace, said rollers being placed at a suitable distance apart along the edges to be drawn together, and means for firmly holding the ends of the lace after tightening; said means including 70 a casing having a chamber and passages for the lace running through said chamber, a sliding button in said casing, dogs pivoted on said button, a spring tending to press the dogs to hold the lace, and an element in 75 said casing engaging with said button to hold it selectively in different positions.

3. A device for lacing shoes and the like comprising guide rollers for the lace, said 80 rollers being placed at a suitable distance apart along the edges to be drawn together, and means for firmly holding the ends of the lace after tightening; said means including 85 a casing having a chamber and passages for the lace running through said chamber, a sliding button in said casing, dogs pivoted on said button, a spring tending to press the dogs to hold the lace, and an element in 90 said casing associated with said button to hold it selectively in different positions, said dogs being adapted to abut against the walls of the casing to disengage them from said lace when the button is situated in one of 95 said positions.

4. A lace securing device comprising a 100 casing having a chamber and passages for the lace running through said chamber, a sliding member in said casing, a pair of dogs pivoted on said sliding member and tending to grip the lace, and a locking element for said sliding member.

5. A lace securing device comprising a 105 casing having a chamber and passages for the lace running through said chamber, a sliding button in said casing, a pair of dogs pivoted on said button and tending to grip the lace, and an element in said casing engaging with said button to hold it selectively in different positions.

6. A lace securing device comprising a 110 casing having a chamber and passages for the lace running through said chamber, a sliding button in said casing, a pair of dogs pivoted on said button and tending to grip the lace, and an element in said casing associated with said button to hold it selectively in different positions, said dogs being adapted to abut against the walls of the chamber to disengage them from said lace when the button is situated in one of 115 said positions.

In testimony whereof I affix my signature.

WILLIAM J. HART. [L. S.]
